US00D880336S

(12) **United States Design Patent** (10) Patent No.: **US D880,336 S**
(45) Date of Patent: ** Apr. 7, 2020

(54) **WATCH**

(71) Applicant: **LVMH Swiss Manufactures SA**, La Chaux-de-Fonds (CH)

(72) Inventor: **Christoph Behling**, London (GB)

(73) Assignee: **LVMH SWISS MANUFACTURES SA**, La Chaux-de-Fonds (CH)

(**) Term: **15 Years**

(21) Appl. No.: **35/506,404**

(22) Filed: **Sep. 12, 2018**

(80) **Hague Agreement Data**

Int. Filing Date: **Sep. 12, 2018**

Int. Reg. No.: **DM/102983**

Int. Reg. Date: **Sep. 12, 2018**

Int. Reg. Pub. Date: **Mar. 15, 2019**

(30) **Foreign Application Priority Data**

Mar. 20, 2018 (CH) 143921

(51) **LOC (12) Cl.** **10-07**

(52) **U.S. Cl.**

USPC **D10/126**

(58) **Field of Classification Search**

USPC 10/30-39, 127, 128-129

See application file for complete search history.
